PHONOGRAPH ARRANGEMENT

Charles W. Dann, Orange, and Richard M. Somers, West Orange, N. J., assignors to Thomas A. Edison, Incorporated, West Orange, N. J., a corporation of New Jersey

Application November 8, 1943, Serial No. 509,518

13 Claims. (Cl. 274—18)

1

Our invention relates to phonograph arrangements wherein two or more phonographs are intercoupled for sequential operation, and relates particularly to a unitary system for intercoupling a pair of separate phonographs of the dictating-machine type, which system is adapted so that it may be readily attached to the machines and be readily detached when the separate dictating machines are to be used singly.

Many establishments have as part of their office equipment two or more dictating machines which are normally used singly during odd hours of the day for dictating reports, letters, memoranda, etc. At these same establishments there may be occasional need for a machine for recording and reproducing matters of a continuous character such as conference proceedings, telephone conversations, etc.; but it may not appear economically justifiable to purchase a special dual machine just for this purpose. By our invention, however, two such single machines on hand may be readily interconnected for recording and reproducing relatively continuous matters. This is accomplished by providing a coupling apparatus of relatively small cost which can be readily attached to two separate dictating machines to interconnect them for sequential operation and be also readily detached so that the separate machines may be used singly as needed. It is accordingly a general object of our invention to enable normally singly-used dictating machines to be interconnected for sequential operation by the mere attachment of a simple unitary coupling system thereto.

Our invention has been adapted to acoustical-type phonographs such as are disclosed in Langley Patent No. 2,150,554, and we do herein illustrate and describe our invention in connection with this type of phonograph. It will however be understood that we intend no unnecessary limitation of our invention to this type of phonograph for the broader aspects of our invention have application to phonographs generally.

Acoustical-type phonographs, or dictating machines, are provided with speaking tubes and on these speaking tubes there are provided manually operable controls for putting the machines into and out of operation. In accordance with the abovementioned Langley patent, the speaking tube and affixed controls each have a separable connection with the phonographic machine by which they may be readily detached as a unit, this facility for detachment having been provided so that the speaking tube may be removed when the machine is not in use and the machine be

2

then enclosed by a small closely-fitting cabinet. Our invention is particularly applicable to this type of phonograph such as is now manufactured and sold, for it may comprise a pair of interconnected control or coupling units that may be mounted on the machines in the place of the speaking tubes, which coupling system may be adapted to interconnect the control systems of the two phonographs so that, on completion of a traversal of the sound-translating device across the record of one machine, the other machine will be automatically started, and vice versa, whereby to provide a continuous phonograph operation. As an additional feature of this particular application of our invention, there may be provided an electro-acoustical transducer in each coupling unit for conditioning the acoustical machine for recording electrical sound-representing signals. This conversion of the machines for recording and reproducing electrical signals is highly important because sequential phonograph arrangements are used commonly for recording conference proceedings and the like, wherein a large amplification of the voice energy is needed to obtain a satisfactory level of recordation on the record.

Our invention contemplates that the coupling units be interconnected by a flexible means, and that this means may be either of a mechanical or electrical type. We preferably employ, however, a flexible mechanical connection—suitably, for example, a Bowden wire—for we find this type of connection permits a great simplification in the structure of the coupling system, provides a wide latitude in control of the phonographic machines and assures a dependable operation.

It is an object of our invention to provide improved means for intercoupling phonographs for sequential operation.

It is another object to provide phonographs with a unitary intercoupling system therefor which may be readily attached to interconnect a plurality of the phonographs for sequential operation, and may be detached to permit the separate phonographs to be used singly, as desired.

It is another object to provide a unitary coupling system which is adapted for attachment to phonographs as now constructed for interconnecting pairs of phonographs for such sequential operation, and which may be readily detached to permit the separate phonographs to be used singly, as desired.

It is another object to provide a unitary system for intercoupling phonographs for sequential operation which permits the separate phonographs to be used singly, as desired.

It is another object to provide a unitary system for intercoupling phonographs for sequential operation which permits the phonographs so intercoupled to be differently positioned relative to one another as may be convenient.

It is another object to provide a unitary attachable system for interconnecting a pair of phonographs for sequential operation and for concomitantly converting the audio systems of such phonographs for recordation and reproduction of electrical sound-representing signals.

It is a further object to provide improved means for intercoupling phonographs for sequential operation, which is simple in construction, flexible in control and dependable in operation.

These and other objects of our invention will more fully appear from the following description and the appended claims.

In the description of our invention reference is had to the accompanying drawings, of which:

Figure 1 is a partial elevational view of an acoustical-type phonograph to which the disclosed illustrative embodiment of our invention is adapted to be applied;

Figure 2 is a top plan view of the sound-translating device of such phonograph as seen with the speaking tube detached;

Figure 3 is a vertical sectional view of such acoustical-type phonograph, taken on the line 3—3 of Figure 9 but with parts broken away, and showing one of the coupling units of our invention applied thereto;

Figure 4 is a partial bottom view of one such coupling unit with a cover part removed to show the interior construction thereof;

Figure 5 is a partial sectional view of one such coupling unit taken on the line 5—5 of Figure 4;

Figure 6 is a top plan view, with the cover removed, of one such coupling unit;

Figure 7 is a detailed sectional view taken on the line 7—7 of Figure 6;

Figure 8 is a detailed view taken on the line 8—8 of Figure 6;

Figure 9 is a partial front view of two phonographic machines as intercoupled by our invention;

Figure 10 is a diagrammatic view of the circuits and mechanism of a dual phonograph arrangement according to our invention; and

Figure 11 is a perspective view of the rotary switch structure of one of the coupling units.

In the drawings there is shown a common variety of acoustical-type dictating machine. As appears in Figures 1, 3 and 9 this machine has a carriage 1 for a sound-translating device 2, which is mounted slidably on a pair of cross rods 3 and 3a for traveling movement along a record support 4. The record support is typically of a mandrel type adapted for supporting a cylindrical record 5. The cross rods are carried by upright side standards 6 of a frame 7 and the record support or mandrel has a central shaft 8 journalled at one end to an intermediate standard 9 of the frame 7. Rotation of the mandrel is produced by a motor 10 (only diagrammatically shown in Figure 10) which transmits its power by way of a belt 11 to a drive pulley 12. This pulley is journalled to the left standard 6 of the frame and is coupled by way of a clutch 13 to the mandrel shaft. The motor 10 also has a drive connection to the carriage 1 for feeding the translating device along the record 5. This drive connection is completed by way of a feed screw 14 that is journalled to the standards 6 and coupled by gearing 15 to the mandrel shaft,

and a feed nut 16 which is pivoted to the carriage 1 for movement into and out of engagement with the feed screw. This above-described mechanism for producing a relative progressive movement between the translating device 2 and record 5—that is, a rotation of the record and concomitant traveling movement between the translating device and the record—we herein refer to as the operating or drive mechanism of the machine.

In the usual acoustical-type phonograph the power supply circuit for the motor 10, which is referred to as 17 in Figure 10, serially includes a so-called hook switch 18. This hook switch comprises a pivoted arm 19 which projects forwardly from the frame 7 and serves as a support, during non-use of the machine, for a speaking tube 20, this tube being provided for conducting sound to and from the translating device 2 as is shown in Figure 1. The weight of the tube on the arm 19 serves to hold the switch 18 open and keep the motor 10 idle during non-use of the machine, but when the tube is removed the arm 19 is moved upwardly under the influence of a spring (not shown) to close the circuit 17 and start the motor running.

The clutch 13 is controlled by an electromagnetic clutch device 21 mounted underneath the frame 7. This device is coupled to the clutch by way of a link 22 and a lever 23 which is shown in Figures 3 and 9. The clutch device is preferably constructed according to U. S. Langley Patent No. 1,380,486, to which reference may be had for details of its construction. For the present purpose, the clutch device is sufficiently described by the statements that it comprises a pair of start and stop electromagnets 24 and 25 (see Figure 10), a pivoted armature 26 which is connected to the aforementioned link 22 and attractable alternately by the electromagnets upon their respective energizations, and circuit means for automatically opening the circuit of the electromagnet last energized upon attraction of the armature thereto and for concomitantly preparing the circuit of the other electromagnet for next energization. This circuit means may comprise a single-pole double-throw switch having a pole member 27 connected to one side of the power supply line 17 and operated directly by the armature 26, and cooperating switch contacts 28 and 29 connected serially to the respective electromagnets and so positioned that the contact connected to one electromagnet is engaged by the pole member 27 when the armature has been attracted to the other electromagnet, and vice versa.

For controlling the clutch device 21, there is provided a manual single-pole double-throw switch 30 which is typically placed on the outer portion of the speaking tube 20 as is shown in Figure 1. This switch has its pole member 31 connected to one side of the power line 17 which is opposite to that to which the pole member 27 is connected and has its switch contact members 32 and 33 connected respectively to the start and stop electromagnets 24 and 25. The pole member of this manual switch is biased to stop position—that is, a position wherein it is closed with the contact member connected to the stop coil. On depressing the pole member 31 to make contact with the other contact member, current is supplied momentarily to the start electromagnet and the armature is actuated to engage the clutch; vice versa, on releasing the pole member 31 current is supplied momentarily to the stop

electromagnet and the armature is attracted to disengage the clutch.

The sound-translating device 2, which may have any suitable construction, is herein illustrated as being of the type described in Dunning et al. Patent No. 2,279,227 to which reference may be had for details of its construction. For the present purpose the device is sufficiently described as having a tubular neck 34 for conducting sound to and from the device, recording and reproducing styli 35 and 36 for cooperation with the record 5, and a pair of lifting fingers 37 for selectively raising and lowering the styli into and out of engagement with the record. These lifting fingers are pivoted to the carriage 1 and controlled by a cam member 38 that is splined at 39 to the cross rod 3 (see Figure 3). To control these fingers, there is a hand lever 39 which is pivoted at 40 to the carriage and coupled by a link 41 to the cam member, the rod 3 being journaled in the standards 6 to permit the cam member to be rocked back and forth by the hand lever. The control action of the hand lever is typically such that when the lever is in the raised position it occupies in Figure 1, the reproducing stylus is in engagement with the record; that when the hand lever is in a lowered position indicated by dash-dot lines in Figure 1, the recording stylus is in engagement with the record; and that when the lever is at a mid or neutral position both styli are held raised from the record.

The hand lever 39 is also adapted to disengage the feed nut 16 from the feed screw 14 when the lever is in the neutral position abovementioned. In order that the feed nut may be so controlled, it is mounted on a lever 42 which is pivoted at 43 to the carriage 1 as shown in Figure 3. A spring 44 acts on the lever 42 and urges the feed nut into engagement with the feed screw. When the hand lever 39 is in recording and reproducing positions, the lever 42 is under the sole influence of the spring 44 and the feed nut is then engaged. However, when the hand lever is moved to neutral position, a pin 45 on the cam member 38 engages a forwardly-extending arm 42a of the lever 42 and cams this lever against the restraining force of the spring 44 to disengage the feed nut.

Surrounding the tubular neck 34 of the sound-translating device 2 is a cylindrical housing 46 (see Figure 3) made of an insulating material such as of Bakelite. This housing fits into the lower part of a circular upstanding flange 47 provided on the frame of the translating device 2. It is held in place by pins or screws 46a as shown in Figure 2. This housing has four equidistantly spaced spring terminals 48. Three of these terminals are connected to the clutch device 21 by the leads 49, these being the leads which connect the manual switch 30 to the clutch device as aforementioned; a fourth lead 49 shown in Figure 2 serves with the lead to the pole of switch 30 to supply power to a signal lamp 50 typically provided on the speaking tube 20 as shown in Figure 1. From the housing 48 these leads extend through an apertured boss 47a of the flange 47 and then through a cable 51 along the side of the carriage 1 to below the frame 1. The spring terminals 48 respectively carry contact buttons 52 which extend radially inwardly through the housing 46. On the inner part of the speaking tube 20 there is a circular cap 53 which is adapted to fit swiveling onto the flange 47. Extending down from the central portion of this cap is a short tube 54 which is adapted to

telescope on the tubular neck 34 exteriorly thereof. The details of construction of this tube 54 are not shown in the drawings since they are the same as of the corresponding part of our invention hereinafter described. For the present, it may be noted that this tube 54 is typically made of an insulating material such as of Bakelite, that it has four equidistantly spaced arcuate terminals set into the exterior surface thereof and connected to the manual switch 30 and signal lamp 50 in the manner aforementioned, and that when the cap 54 is in mounted position these terminals contact the buttons 52 to complete the connections from the manual switch 30 and signal lamp 50 to the power supply circuit 15 and clutch device 21. Additionally, it may be noted that for releasably retaining the cap 53 swivelingly to the translating device, the tube 54 is provided with an exterior annular groove which the contact buttons 52 engage under their spring pressure, and that for limiting the range of swiveling movement of the speaking tube the cap thereof is provided with a front fin 53a which engages a wide notch 47b provided in the flange 47 of the translating device.

It will be understood that the apparatus hereinabove described is common to dictating machines such as have been heretofore manufactured and sold, and that this apparatus forms a part of our invention only by way of its combination with the apparatus hereinafter described.

In accordance with our invention, we provide a unitary coupling system for phonographs which comprises two identical control or coupling units 55 having a flexible interconnection 56 as shown in Figure 9. These coupling units are adapted to be attached to the respective phonographs. In the present illustrative embodiment of our invention, these units are attached to the phonographs in the place of the detachable speaking tubes 20, and by that attachment the two dictating machines are intercoupled for automatic sequential operation and are adapted for recording and reproducing electrical sound-representing signals, as aforementioned.

Each coupling unit 55 has a frame 57 made suitably of stamped flat metal parts and a cover 55c. On the bottom of this frame there is secured a hollow cylindrical Bakelite housing 58 from which projects a central tube 59 adapted to telescope over the tubular neck 34 of the sound-translating device, this being the tube corresponding to the tube 54 of the speaking tube. This tube 59 has four equidistantly-spaced arcuate terminals 60 embedded in the exterior surface thereof and has an annular exterior groove 61 as shown in Figure 3. When the coupling unit is in mounted position, the contact buttons 52 engage the groove 61 under their spring pressure to make contact with the respective terminals 60 and to detent the coupling unit to the sound-translating device. The terminals 60 extend up into the housing 58 and are therein provided with wings 62 which are bent over and anchored by pins 63 to the upper part of the housing as shown in Figure 4. Across the bottom of the housing 58 is an annular closure plate 64 (see Figure 5) which is held in place by screws 65.

Mounted directly above the bottom plate of the frame 57 is an electroacoustical transducer 66 shown in Figure 5. This transducer may typically comprise a headphone of the piezo-electric or magnetic type, the former being however preferred as it is typically very thin. This transducer has a tubular sound outlet 67, preferably

of a conical exterior shape, which is adapted to engage the upper inner edge of the tubular neck 34 and extend into the neck to form a substantially closed sound coupling between the transducer and translating device. The transducer is secured to the frame 57 by an overlying bracket 68 which engages an upturned apertured lug 67a of the frame at one end and is held to the frame by a screw 69 at the other end. Electrical connection to the transducer is made by means of a 10 cable 70.

Mounted above the transducer 66 is a single-pole double-throw switch 71 of the rotary type. This switch has three flat spring arms 72 mounted insulatedly in cantilever fashion on a flat 15 plate 73 that is supported by a bracket 74 of the frame 57. The arms are spring-biased downwardly against a pivoted switch structure 76 shown in Figure 11. This switch structure includes a shaft 77 journalled in a pair of apertured lugs 78 of the frame 57, which shaft has an extending end portion thereof offset to form a crank 77a for the switch structure. On the shaft 77 between the lugs 78 there are secured front and back insulating plates 79 and 80 which have sector shapes such as are indicated in Figure 7. These insulating plates are secured rigidly together but in spaced relation along the shaft by means of two rivets 81 and pairs of intervening spacers 82 on the rivets. Each of the insulating plates has a peripheral surface at constant radius relative to the shaft 77, or dwell 83, and a receding peripheral surface or recess 84. The recess on the front insulating plate 79 is at the clockwise end of the dwell 83 thereof while the recess of the back plate 80 is at the counterclockwise end of the dwell thereof, and in the angular range between the recesses there is a substantial overlap of the dwells of the respective insulating plates. At the recesses of the respective insulating plates there are secured identically shaped switch contact members 85. The contact surfaces of these switch members extend beyond the recesses and form an even arcuate extension of the dwells of the respective plates. 40 These switch contact members are held to the insulating plates by the rivets 81 but, being identically shaped, they are pointed in opposite directions. Between the spacers 82 on each rivet 81 there is clamped a third switch contact member 86 having a dwell along its full peripheral surface. The rivets 81, spacers 82 and switch contact members 85 and 86 are all made of a conductive material such as of brass, and are accordingly electrically connected together. It is 45 against the dwells of the insulating plates 79 and 80 and of the switch contact members 85 and 86 that the arms 72 slidably bear.

The switch arms 72 are connected to three of the arcuate terminals 60 of the coupling unit by a three-wire cable 88; the fourth one of the terminals 60—the one contacting the contact button 52 that connects to the lamp 59 when the speaking tube 20 is attached—being not used. This cable 88 may fold over the side of the coupling unit and enter through a ferrule 89 into the cylindrical housing 58 wherein the leads thereof are soldered to the three respective terminals just mentioned. These leads are so connected to the terminals 60 that when the coupling unit is in mounted position the central one of the arms 72—which is the pole member of the rotary switch 71—is connected directly to one side of the power supply line 17 (see Figure 10), the front one of the arms 72 is connected to the

start electromagnet 24, and the back one of the arms 72 is connected to the stop electromagnet 25.

When the shaft 77 is in a most counterclockwise position—a position wherein the crank 77a thereof is inclined downwardly and to the right as shown in Figure 9—the forward switch arm 72 engages the respective switch contact member 85 and a closed circuit is formed from the central or pole arm 72 through the front arm 72 to the start electromagnet, this being the start position for the switch 71. Provided of course the hand lever 39 is in recording or reproducing position and the hook switch 18 is closed, which it normally will be, the left machine of the phonograph arrangements shown in Figures 9 and 10 will now be in operation and the translating device thereof will be advanced gradually across the rotating record 5. When the translating device nears the end of its rightward travel—which we herein term its terminal position—the crank 77a is impinged against the right standard 6 and the shaft 77 is turned gradually in a clockwise direction. (In order that the coupling unit 55 will be restrained against being turned by the force exerted by the standard 6 against the crank 77a, the coupling unit has a bracket 90 on its front lower portion which engages the notch 47b of the flange 47.) As the shaft 77 is so turned the front switch arm 72 first breaks connection with the respective switch contact member 85 and enters onto the dwell 83 of the insulating plate 79, but it will be understood that this break in the circuit connection between the front and middle arms 72 produces no direct control action because, as afore-explained, the circuit of the start electromagnet is already open, being opened automatically as an incident of the engagement of the clutch. Both the front and back arms now ride on the dwells 83 of the respective insulating plates 79 and 80, but in a further continued advance of the carriage the shaft 77 is turned further clockwise to cause the back arm 72 to ride onto the respective contact member 85. This closes the circuit between the central and back arms 72 and supplies current to the stop electromagnet to cause the clutch 13 to be disengaged.

The connection 56 between the coupling units is for intercoupling the rotary switches 71 so that the operation of either of these switches will cause the other to be automatically operated. Preferably, the connection 56 is of Bowden-wire type comprising a flexible armored cable 91 which is anchored at the ends into rigid tubular parts 57b provided on the frames 57, and a flexible wire 92 which extends through this cable. The ends of this wire are connected to arms 93 secured to the shaft 77, and the length of the wire is so selected that, with the wire taut, the following two conditions will be fulfilled: (1) the rotary switch 71 of one coupling unit will be in stop position when that of the other unit is in start position, and (2) the said one switch will enter start position when the other has been moved midway from start to stop position. It will be understood that the start position of each switch begins when initial contact is made between the front switch arms 72 and respective switch members 85, and that to fulfill condition (2) without imposing strain on the interconnection 56, the forward arm 72 of the rotary switch 71 of the machine last started is permitted to move beyond start position, with the arm riding across the face of the respective contact member 85 as appears in Figure 7, while the rotary switch 71 of

the other machine is moved from mid to stop position.

The sequential operation of the two phonographs in the dual arrangement above described will be understood to be as follows: First, suppose that the carriage of the idle machine is resting in initial position and that the carriage of the operating machine is being driven across the record, the operating machine being in this case the leftward one of the two machines shown in Figures 9 and 10. When the carriage of the operating machine nears terminal position to cause the switch 71 thereof to be moved from start position to mid position, the switch 71 of the other machine is moved from stop position into start position and the idle machine is thereby started. Both machines will then be in operation while the switch 71 of the first-operating machine is being moved onwardly from mid position to stop position, whereupon the first-operating machine is automatically stopped. During the traversal of the carriage of the second machine across the record, the attendant will shift the hand lever 39 of the first machine to neutral position, manually return the carriage to initial position, replace the used record, and then return the hand lever 39 back to operating (recording or reproducing) position. When the carriage of the second machine nears its terminal position, it will start the first machine and thereafter stop itself. Since in this procedure there is an overlap of operation of both machines at the transition in operation from one machine to the other, there is provided a continuous phonograph operation by the combined machines.

In order that there may not be any heavy strain imposed on the Bowden wire 92, or carriage feed mechanisms of the machines, should the attendant let the carriage of one machine rest in its terminal position, with the feed mechanism of that machine engaged, while the other machine is moved into its terminal position, there is provided a yieldable coupling between the units 55 which comprises a torsion spring 95 connected between the arm 93 and shaft 77 of each unit. The arm 93 may have a hub portion in the form of a bail (see Figure 6); and adjacent this hub portion there is an arm 96 which is rigidly secured to the insulating plate 79 of the rotary switch structure 76 by a stud 96a and provided with a turned-over lug 97 that overhangs a short arm 98 of the bail. The spring 95 is hooked between this lug and the arm 93, and normally yieldably presses the short arm 96 against the lug 97. However, on moving both switches 71 into stop position at the same time, this spring 95 yields so as not to impose any heavy strain on the intercoupling between the two units 55.

In some instances it may be desired to have both switches 71 placeable simultaneously into start position so that both machines may operate at the same time. In order that this may be done the Bowden wire is linked to the arm 93 through a one-way coupling 98 shown in Figure 3. For instance, the ends of the wire may connect to rigid links 99 which pass slidably through apertured studs 100, that are pivoted to the arms 93, and then terminate in heads 101. In normal operation the studs bear against the heads to provide a tension coupling between the pivoted switch arms 93, but when both switches are shifted simultaneously to start position the studs 100 will slide downwardly along the links 99.

By interconnecting the coupling units 55 with a mechanical means as above described we ob-

tain an entirely dependable and stable operation of the phonographs without ever encountering any instable or chattering conditions of the clutch-operating mechanisms 21 such as will sometimes occur should they be electrically interconnected. Also, the use of a mechanical type of interconnection permits a wide flexibility in control over the phonograph arrangement, such as is described in the two foregoing paragraphs, by the addition of very simple means.

It will be understood that the cables 70 to the transducers 66 constitute the signal input circuits for the phonographs when they are to be operated for recording and the signal output circuits when the phonographs are to be operated for reproducing. Thus, when the phonographs are used to record from and to reproduce into electrical sound systems involving electrical amplification, the cables 70 will be connected to the output of the amplifier of such sound system during recording and to the input of the amplifier during reproducing, such amplifier and circuit control connections as may be provided being not herein necessary to show.

We have herein particularly shown and described an embodiment of our invention as applied to an existing type of dictating machine. This embodiment illustrates clearly the broader aspects of our invention as well as specific details of one preferred construction thereof, but no unnecessary limitation of our invention to the details of this embodiment or to the details of construction of the dictating machine to which our invention is herein applied is intended. It will, for example, be understood that our invention is applicable to phonographs wherein the relative progressive movement between the record and translating device is produced by moving either the record or the translating device with respect to the other, that the drive or operating mechanism may be controlled by wholly electrical or mechanical means, and that the audio system for the machine may be wholly of the acoustical or electroacoustical type, for the adaptation of our invention to phonographs differing in these and other respects will be readily apparent to those skilled in the art from the foregoing disclosure. Also, it will be understood that the embodiment herein disclosed may be modified in other ways without departing from the scope of our invention, which we endeavor to express according to the following claims.

We claim:

1. In a dual phonograph arrangement comprising two separate phonographic machines respectively including a rotatable record support, a phonographic translating device and an operating mechanism for rotating said support and concomitantly producing a relative progressive movement between said support and translating device; a detachable unitary system intercoupling said machines for sequential operation comprising two control units respectively detachably mounted on said machines and adapted for starting and stopping said operating mechanisms respectively; a coupling between said control units, including a flexible operable portion permitting independent movement of said machines relative to one another, for causing either unit to be placed into start position upon the other being operated into stop position, and vice versa; and means, coupled to each translating device and operated by the relative progressive movement between said record support and the

translating device for causing operation of the respective control unit.

2. A dual phonograph arrangement comprising two separate phonographic machines respectively including a rotatable record support, a movably mounted phonographic translating device and an operating mechanism for rotating said support and concomitantly moving said translating device from initial to terminal positions: a detachable unitary system intercoupling said machines for sequential operation comprising two control units respectively detachably mounted on said machines and adapted for starting and stopping said operating mechanisms respectively; means coupled to said units and operated by said respective translating devices in the movements thereof into terminal positions for placing the respective units into stop position; and a coupling between said control units, including a flexible operable portion permitting said machines to be moved independently of one another for causing either unit to be placed into start position upon the other being operated into stop position.

3. A detachable system for coupling for sequential operation two phonographic machines each having an operating mechanism and a device for putting the mechanism into and out of operation, said system comprising a control unit for each of said devices; separable means for detachably mounting said control units onto said machines respectively and for concurrently effecting operative control connections of the units to said devices respectively; a control mechanism on each of said units movable into start and stop positions to put the respective operating mechanism into and out of operation, each of said units and respective devices being adapted to maintain the respective operating mechanism in operation during movement of the respective control member from start to stop position and to maintain the mechanism out of operation during movement of the control member from stop to start position; and means intercoupling said control units, including a flexible operable portion permitting independent movement of said machines relative to one another, for causing either control member to be moved into start position upon the other control member being moved through a first portion of its travel from start to stop position.

4. The subject matter as set forth in claim 3 wherein said intercoupling means comprises a flexible mechanical connection between said control members, and wherein each control member has a freedom of movement beyond start position to permit either control member to be moved freely through the final portion of its travel from start to stop position.

5. The subject matter as set forth in claim 4, wherein said intercoupling means comprises a mechanical connection between said control members and yieldable means in said connection for permitting either control member to be moved onwardly into stop position while the other control member is retained in stop position.

6. The subject matter as set forth in claim 3, wherein said intercoupling means comprises a mechanical connection between said control members and a one-way coupling in said connection for permitting both control members to occupy start positions at the same time.

7. A unitary detachable system for coupling for sequential operation two separate phonographic machines each having an operating mechanism and a device for putting the mech-

anism into and out of operation, said system comprising a pair of control units; separable means for detachably mounting said control units onto said machines respectively and for concurrently effecting operative control connections of the units to said devices, each of said control units having a control member movable into start and stop positions to control the respective one of said devices; and a flexible Bowden wire coupling between the control members of said unit, permitting independent movement of said machines relative to one another, for causing either control member to be moved into start position upon the other control member being moved towards stop position.

8. In an arrangement for intercoupling a pair of phonographic machines for sequential operation, said machines respectively including a record support, a phonographic translating device and an operating mechanism for producing a traveling movement of said device relative to said support: the combination of a control unit for each of said operating mechanisms; separable means for detachably securing said control units to said respective phonographic translating devices and for concurrently effecting operative control connections of said units with said operating mechanisms respectively; control members on said units movable into start and stop positions to put said operating mechanisms into and out of operation; flexible means intercoupling said control units and permitting independent movement of said machines relative to one another for moving the control member of one unit into start position upon the other control member being moved to stop position; and members on said machines for abutting against said control members and moving the same between start and stop positions in response to the traveling movement of said respective translating devices.

9. In an arrangement for adapting a pair of separate acoustical-type phonographic machines for recording electrical sound-representing oscillations and intercoupling said machines for sequential operation, said phonographic machines respectively comprising a record support, a sound-translating device, an operating mechanism for producing a progressive relative movement between said support and translating device and a control connection for said operating mechanism terminating at said translating device: the combination of a pair of coupling devices each including an electroacoustical transducer and a control unit, said coupling devices being adapted for detachable mounting onto said respective sound-translating devices in position wherein each transducer feeds into the respective translating device; means for connecting said control units with said respective control connections upon mounting said coupling devices, said control units being operable into start and stop positions for putting said respective mechanisms into and out of operation; and a coupling between said control units, including a flexible operable portion permitting independent movement of said machines relative to one another, for moving either unit into start position upon the other being moved to stop position.

10. In an arrangement for adapting a pair of separate acoustical-type phonographic machines for recording electrical sound-representing oscillations and intercoupling said machines for sequential operation, said phonographic machines respectively comprising a record support, a sound-translating device, a sound-transmission tube

13

extending from said device, an operating mechanism for producing a progressive relative movement between said support and translating device and control circuit leads for said operating mechanism and terminating at said sound-translating device: the combination of a pair of coupling devices each including an electro-acoustical transducer detachably mountable onto said respective sound tubes, an electrical switch and circuit means for connecting said switch to the said respective circuit leads upon mounting the transducer, said switches being movable into start and stop positions to put said respective operating mechanisms into and out of operation; a flexible operable connection between said switches, permitting independent movement of said machines relative to one another for moving either switch into start position upon the other being moved to stop position; and means for causing said switches to be operated by a relative progressive movement of said respective translating devices.

11. An attachable system for coupling acoustical-type phonographs having movable sound-translating devices, operating mechanisms for moving said translating devices from initial to terminal positions, and control circuits for said mechanisms terminating at said respective translating devices, said system comprising two electroacoustical transducers adapted to be mounted on said translating devices respectively; a pair of switches carried with said transducers respectively; circuit means for automatically electrically connecting said switches to said respective control circuits upon mounting said transducers; means interconnecting said switches for causing either to be operated by the other; and stationary means on the phonographs for cooperation with said switches respectively to operate the switches into stop positions in response to movement of said respective translating devices into terminal positions.

12. In a dual phonograph arrangement comprising two separate phonographic machines each including a rotatable record support, a record cooperable translating device of the acoustical type, drive means for effecting a relative traveling movement between said translating device and support, and control connections to said drive

14

means terminating at said device: a unitary detachable apparatus intercoupling said machines for sequential operation and adapting the machines for operation with electrical sound-representing audio systems, comprising a pair of coupling units detachably connected to said translating devices, each of said coupling units including an electroacoustical transducer coupled acoustically with the respective translating device, and a control device having operable coupling with said control connections when the unit is so mounted, said control devices being operable into start and stop positions to put the respective drive means into and out of operation; a coupling between said units, including a flexible operable portion permitting independent movement of said machines relative to one another, for causing one control device to be moved into start position as the other is moved into stop position, and vice versa; and means for causing said control devices to be operated by relative traveling movement between said respective translating devices and record supports.

13. In a dual phonograph arrangement comprising two separate phonographic machines respectively including a phonographic translating device and an operating mechanism adapted for producing a traveling movement of said device between initial and terminal positions: a detachable unitary system intercoupling said machines for sequential operation comprising two control units respectively detachably mounted on said machines and adapted for starting and stopping said operating mechanisms respectively; a flexible coupling between said control units, permitting independent movement of said machines relative to one another, for causing each unit to be operated by the other; and means, comprising an element coupled to each translating device and a respectively associated element mounted on the machine in the path of movement of said first-mentioned element, for causing operation of the control unit of each machine in response to a traveling movement of the respective translating device.
